UNITED STATES PATENT OFFICE.

FREDERICK C. OVERBURY, OF NEW YORK, N. Y., ASSIGNOR TO FLINTKOTE MANUFACTURING COMPANY, OF RUTHERFORD, NEW JERSEY, A CORPORATION OF NEW JERSEY.

ROOFING-STRIP.

No. 876,009.

Specification of Letters Patent.

Patented Jan. 7, 1908.

Application filed March 18, 1907. Serial No. 362,987.

To all whom it may concern:

Be it known that I, FREDERICK C. OVERBURY, of New York, in the county of New York and State of New York, have invented 5 certain new and useful Improvements in Roofing-Strips, of which the following is a specification.

This invention relates to elongated strips of flexible waterproof material of indeterminate length, suitable for use in covering roofs and walls of buildings by laying the strips in courses, one edge of each strip partially overlapping the strip below it. For convenience, I have denominated the articles, to which my invention relates, as a "roofing strip" without intending to limit the application for these strips to roofs alone.

The invention has for its object to provide a roofing strip, capable of being laid with 20 either side outermost, and adapted to produce a roof or wall surface either of a single color throughout, which color may be either of two contrasting colors, or capable of being laid so that the color of the exposed surface 25 of each strip will contrast with the color of the adjoining strip or strips.

The invention consists of a roofing strip of the character above indicated, having its opposite sides differently colored.

30 Of the accompanying drawings, forming a part of this specification,—Figure 1 represents a side view of a portion or fragment of a roofing strip, shaded to represent a given color, such as red. Fig. 2 represents a side 35 view of the opposite side of the portion or fragment illustrated in Fig. 1, shaded to represent a different or contrasting color, such as black. Fig. 3 is a section on the line 3—3 of Fig. 2.

40 The same letters of reference indicate the same parts in all the figures.

In carrying out my invention, I provide an 45 elongated flexible water-proof roofing strip a' , made of any suitable material or materials and produced by any suitable process, the strip being of suitable flexibility and being water-proof and adapted to resist the action of rain, wind and solar heat. The strip presents two oppositely facing side surfaces a' 50 and a^2 , said surfaces being differently colored, so that if all the strips are laid with one side, for example the side a' , outward, the surface formed by the assembled strips will present a given color, such as red, and, if laid with the 55 opposite sides a^2 outward, the surface will

present a different color, such as black. The colors red and black are of course named for the purposes of illustration. I desire to be understood as reserving the right to employ any two contrasting colors, one for the side a' 60 and the other for the side a^2 . The colored surfaces a' and a^2 may be produced by any suitable process, care being taken to provide such coloring material and employ such processes as will make the respective colors durable and permanent, and capable of withstanding elemental action.

In the embodiment of the invention here shown, the edge a^3 of the strip is straight and the edge a^4 is serrated, the serrated edge a^4 70 being the lower edge of the strip when the latter is laid. The strips are laid in such manner that the serrated edges will present a diversified appearance on a roof or wall similar to that produced by pointed shingles, the 75 serrations of each strip alternating with those of the strip below it, as shown in my application for Letters Patent of the Untied States, Serial No. 318,903, filed May 26, 1906. My invention is not limited, however, to a strip 80 having a serrated edge, as the lower edge of the strip may be straight, if desired, and parallel with the upper edge, and the lower edge, instead of having angular projections and recesses, may be curved so as to present alter- 85 90 95 90

It will be seen that the strip, characterized as stated, gives the user a choice of either of two colors for the roof or surface to be covered, and also enables the user to produce a variegated surface by alternating the strips 95 so that one strip will present the surface a' outermost, while the next strip will present the surface a^2 outermost.

When the serrated strips are laid so that the color or tint of the exposed side of one 100 strip is differentiated from the color or tint of the exposed side of the next strip, the effect to the eye is to make the serrated edge of each strip of greater thickness than it actually possesses. In other words, the exposed surface 105 of one strip appears to stand out more prominently from the exposed surface of the next strip below it than would be the case if the strips were not differentiated in color or tint.

I claim:

110

As an article of manufacture, an elongated roofing strip serrated at one of its edges and having one of its sides differentiated in color or tint from the other side, both sides being capable of withstanding elemental action, whereby the strip is adapted to be laid with either side outward.

In testimony whereof I have affixed my signature, in presence of two witnesses.

FREDERICK C. OVERBURY.
